Sydney P. Prescott

UNITED STATES PATENT OFFICE.

SYDNEY I. PRESCOTT, OF NEW YORK, N.Y.

DEVICE FOR DESTROYING SUBMARINES.

1,287,743.

Specification of Letters Patent. Patented Dec. 17, 1918.

Application filed May 25, 1917. Serial No. 170,920.

To all whom it may concern:

Be it known that I, SYDNEY I. PRESCOTT, a citizen of the United States, residing at New York, county of New York, and State 5 of New York, have invented a new and useful Improvement in Devices for Destroying Submarines, of which the following is a specification.

This invention relates to a device for destroying submarines, and it has for its main object the production of a device capable of being positioned in the path of movement of one or more submarines, and so arranged that when they come within its range of 15 action, bombs, which are normally supported at or about the surface of the water, are released by mechanism operated by the submarines themselves and permitted to drop through the water to said submarines. A further object is the production of a device of the general character above indicated which shall be operative in the same way at any depth to which a submarine can submerge. A further object of the invention is the production of a device capable of being reloaded or repaired without being withdrawn from its station. With these and other objects not 25 specifically mentioned in view, the invention 30 consists in certain constructions which will be hereinafter fully described and then specifically set forth in the claims hereunto appended.

In the accompanying drawings, which 35 form a part of this specification and in which like characters of reference indicate the same or like parts, Figure 1 is a side elevation of a device constructed in accordance with the invention. Fig. 2 is an end elevation of the device shown in Fig. 1. Fig. 3 is a view similar to Fig. 2, but illustrating the operation of the device. And Figs. 4 and 40 5 are respectively cross-sectional views taken on the lines 4 and 5 in Fig. 1, but shown on an enlarged scale.

In carrying the invention into effect, there is provided a buoyant member, a net pendent therefrom, bombs normally supported by the buoyant member, and means 45 connected with the net and bombs whereby an abnormal downward pull set up by a submarine enmeshed in the net releases the bombs to drop upon said submarine. In the best constructions, the buoyant members 50 are elongated and carry a number of bombs, and the meshes of the pendent net are suffi-

ciently open to permit a submarine to pass part way but not all the way therethrough. In the best constructions also, the net has flexible wire laterals, more flexible verticals, 60 and one or more brails by means of which it may be readily adjusted for use at any depth of water within the range of submer- 65 sion of a submarine. In the best construc- 70 tions also, the bombs are normally supported by and within the buoyant member, preferably in wells extending vertically through said member, so that they may be readily loaded into position and carried with per- 75 fect safety—except to a submarine. In the best construc- 80 tions also, a trip mechanism is utilized for the purpose of releasing the bombs, this trip mechanism being operative only when a submarine is enmeshed in the net and under the bombs. In the best con- 85 structions also, a series of units are coupled together by a flexible connection, such as a chain, and the nets of adjacent units are connected by means of the brails which also serve the purpose of reefing the nets. In 90 the best constructions also, the units are connected in such manner that the device as a whole may be spread by two towboats and moved sidewise by said towboats; or it may be slowly towed in one direction by a 95 single towboat, and when this is done a number of such towing units may coöperate to completely bar the passage of submarines in either direction at any desired location.

The device selected to illustrate the invention is but one of many possible concrete embodiments of the same. The invention therefore is not to be restricted to the precise details of the structure shown and described.

Referring to the drawings, the device selected to illustrate the invention shows a series of units coupled together one behind the other by means of chains 7. Any means of securing these chains to the buoyant 100 members 6 may be employed. It is preferred, however, that quick detachable means be employed for this purpose so that in the event of the destruction of one of the units, it may be readily cut out and the two adjacent buoyant members coupled together. For this purpose a log boom chain having a toggle at each end engaging ring bolts on the buoyant members may be used. The units are all alike and a description of one 105 will therefore answer for a description of all. The buoyant member 6 may be con-

structed of wood or other material in itself buoyant; or if preferred, it may be constructed of metal in a manner well known and needing no description. As shown, the 5 buoyant member 6 is constructed of metal and is provided with an elongated well 8 covered by a hatch cover 9 of any approved construction. Extending vertically through the member 6 from the bottom of the well 8 to the bottom of the member itself, are 10 two pipes 10 and 11; and in each of these pipes is mounted a rod 12, the lower end of which terminates in an eye 13. The purpose of these rods will be hereinafter 15 described. There is further provided three vertical wells 14 extending from the bottom of the elongated well 8 to the bottom of the member 6. These wells 14 are for the purpose of housing bombs 15. Each of the 20 bombs 15 is supported within its well 14 by means of a pair of pawls 16 secured upon a pair of longitudinal shafts 17 located within the main well 8. The pawls 16 engage a flange 18 formed on the upper or 25 rear end of the bomb 15. This flange 18 carries an eyebolt 19, by means of which suitable devices including a hook may be utilized for the purpose of lowering the bomb into a well, or hoisting it therefrom. 30 The eyebolt 19 may, however, be omitted and tongs adapted to engage the bomb flange 18 used instead for loading and unloading purposes. The shafts 17 are provided with arms 20 connected by means of a tension 35 spring indicated at 21. This tension spring normally operates to hold the pawls 16 in engagement with the flange 18 of the bomb. The shaft 17 also carries a pair of cam arms 22 in the wake of each rod 12. Each 40 rod 12 carries at its upper end a cam head 23, and the construction of the cam arms 22 and the cam head 23 is such that a downward movement of either of the rods 12 will rock the shafts 17 and release the bombs, 45 it being understood that the shafts 17 extend along the main well 8 and that a pair of bomb retaining pawls 16 is located in the wake of each bomb well 14. In order that the bombs will not be released by any normal 50 downward pull on the rods 12, each of said rods 12 is fitted with a coiled compression spring 24 bearing against the bottom of the well 8 and the cam head 23. This spring is powerful enough to resist downward 55 pull of the rods 12 at all times and under all conditions except when an abnormal downward pull is set up by a submarine moving across the path in which the device lies.

For the purpose of causing a submarine to exert the abnormal pull on the rods 12 necessary to release the trip mechanism just described, a net is provided. This net consists of laterals 25, 26 and 27, these laterals being constructed of flexible wire rope to

cause them to sink, and each is provided with an eye 28 turned in at each of its ends. The purpose of these eyes will be presently explained. The number of these laterals is determined, first by the depth of a submarine, the laterals being so spaced that a submarine may enter the space between any two adjacent laterals, but cannot pass through; and second, by the depth of the net as a whole, which is designed to be sufficient to block the path of a submarine at any depth to which it can be submerged without being endangered by water pressure. The laterals are held in proper spaced relation by means of verticals 29, these verticals being preferably of more flexible material than the laterals, such for instance as hemp rope, the verticals being secured to the laterals at crossing points by seizings, clove hitches, or other well known fastening means. The upper ends of the verticals nearest the ends of the buoyant member 6 are secured to eyebolts 30 carried by said member. The upper ends of the intermediate verticals are secured to the eyes 13 of the rods 12. The net thus formed is of very open mesh, so that a submarine can pass through any one of the meshes a considerable distance before it begins to pull down on the rods 12 to release the bombs.

For the purpose of connecting adjacent unit nets and for the further purpose of reefing the net as a whole, there are provided a series of rope brails 31, one for each unit. Each brail is bent in to the forward eye of the lowermost lateral of its unit and rove upward through the adjacent eyes of the laterals of adjacent units, as clearly shown in Fig. 1. Its upper end is belayed to a suitable cleat on the deck of the buoyant member of its unit. When the net is extended to its full depth, this brail merely serves to connect the ends of the laterals of adjacent units. When, however, it is desired to reef the net to use it in shoaler water, all of the brails are hauled in until the lateral 27, for instance, is brought up against the lateral 26, or both are brought up against the lateral 25, if necessary.

The operation of the device is as follows: The buoyant members 6 may be connected together by means of the chains 7, in port, with the laterals all brailed close up under the bottom of said members. If preferred, the laterals and verticals may be stopped along the decks of the members. The bombs may also be loaded in the wells 14; and if desired, spare bombs may be carried in convenient racks, not shown, in the buoyant members. So arranged, the device as a whole may be towed to its station and when such station is reached, the brails are slackened away until the desired depth of net is reached. The device is then ready for use and may be used stretched between two tow-

boats; or separate devices may be towed slowly each by one towboat; or both ends of the device as a whole may be anchored. Whenever a submarine pokes its bow into 5 any one of the meshes of the net, it will push the net to one side and careen the buoyant member to some extent. As it moves forward, it exerts a downward pull upon one or more of the verticals 29 connected 10 with the rods 12. This downward pull results in a downward movement of the cam head 23, which in turn forces the cam arms 22 apart and rocks the shafts 17. The rocking shafts in turn throw out the pawls 16 15 and release the bombs 15 in the several wells. It may be here remarked that the number of verticals and the number of bombs carried by each buoyant member is determined by the beam of the smaller submarines it is 20 designed to destroy. It is the purpose to position the bombs in such manner that no matter where a submarine strikes the net, one and probably two falling bombs will strike and destroy it. By an inspection of 25 Fig. 3, it will be readily understood that the action of a submarine in pushing the net to one side, leaves the way clear for the bombs to fall to the submarine without striking the net, the path of a falling bomb being 30 indicated by the dotted line in that figure. It will be remembered that the meshes of the net are open sufficiently to permit a submarine to pass part way but not all the way therethrough. The purpose of this is to 35 bring the wide midship section of the submarine under the buoyant member when the bombs are released. It is probable that a bomb or two exploding against the submarine will not only destroy the submarine, 40 but will destroy the net and possibly the buoyant member of one or more units of the device. In such event, the tender on station will run alongside the break, cut out the damaged or destroyed units, and couple together the two nearest units remaining 45 intact. If, however, the units escape injury and the damaged submarine sinks away therefrom, the tender will come alongside and reload the bomb wells of the buoyant 50 member from which bombs have been dropped. Obviously, the tender may carry a supply of bombs if no spare ones are carried in the buoyant members themselves.

When the device is ordered off station for 55 any reason and back to port, the tender merely brails up the net and the device may then be towed into shoal water and the bombs unloaded there.

What is claimed is:

60 1. A device for destroying submarines comprising a buoyant member, a net pendent therefrom, bombs normally supported by the buoyant member, and means connected with the net and bombs whereby an abnormal 65 downward pull set up by a submarine en-

meshed in the net releases the bombs to drop upon said submarine.

2. A device for destroying submarines comprising an elongated buoyant member, a net pendent therefrom, bombs normally supported by the buoyant member, and means connected with the net and bombs whereby an abnormal downward pull set up by a submarine enmeshed in the net releases the bombs to drop upon said submarine. 75

3. A device for destroying submarines comprising a buoyant member, a net pendent therefrom the meshes of which are sufficiently open to permit a submarine to pass part way but not all the way therethrough, 80 bombs normally supported by the buoyant member, and means connected with the net and bombs whereby an abnormal downward pull set up by a submarine enmeshed in the net releases the bombs to drop upon said 85 submarine.

4. A device for destroying submarines comprising a buoyant member, a net pendent therefrom and having flexible wire laterals and more flexible verticals, bombs normally 90 supported by the buoyant member, and means connected with the net and bombs whereby an abnormal downward pull set up by a submarine enmeshed in the net releases the bombs to drop upon said submarine. 95

5. A device for destroying submarines comprising a buoyant member, a net pendent therefrom and having flexible wire laterals provided with an eye in each end and also having more flexible verticals secured 100 to the laterals at regular intervals to form rectangular meshes sufficiently open to permit a submarine to pass part way but not all the way therethrough, bombs normally supported by the buoyant member, and means connected with the net and bombs whereby an abnormal downward pull set up by a submarine enmeshed in the net releases the bombs to drop upon said submarine. 105 110

6. A device for destroying submarines comprising a buoyant member, a net extending the full length of said buoyant member and pendent therefrom, bombs normally supported by the buoyant member, and means connected with the net and bombs whereby an abnormal downward pull set up by a submarine enmeshed in the net releases the bombs to drop upon said submarine. 115 120

7. A device for destroying submarines comprising a buoyant member, a net pendent therefrom, bombs normally supported by and within the buoyant member, and means connected with the net and bombs whereby an abnormal downward pull set up by a submarine enmeshed in the net releases the bombs to drop upon said submarine. 125

8. A device for destroying submarines comprising a buoyant member, a net pendent 13

therefrom, bombs normally supported in wells extending vertically through the buoyant member, and means connected with the net and bombs whereby an abnormal downward pull set up by a submarine enmeshed in the net releases the bombs to drop upon said submarine.

9. A device for destroying submarines comprising a buoyant member, a net pendent therefrom, bombs normally supported by the buoyant member, and a trip mechanism connected with the net and bombs whereby an abnormal downward pull set up by a submarine enmeshed in the net releases the bombs to drop upon said submarine.

10. A device for destroying submarines comprising a series of units coupled together each unit including a buoyant member, a net pendent therefrom, bombs normally supported by the buoyant member, means connected with the net and bombs whereby an abnormal downward pull set up by a submarine enmeshed in the net releases the bombs to drop upon said submarine, and means for coupling the unit nets.

11. A device for destroying submarines comprising a series of units flexibly coupled together each unit including a buoyant member, a net pendent therefrom, bombs normally supported by the buoyant member, means connected with the net and bombs whereby an abnormal downward pull set up by a submarine enmeshed in the net releases the bombs to drop upon said submarine, and means for coupling the unit nets.

12. A device for destroying submarines comprising a series of units connected by chains each unit including a buoyant member, a net pendent therefrom, bombs normally supported by the buoyant member, means connected with the net and bombs whereby an abnormal downward pull set up by a submarine enmeshed in the net releases the bombs to drop upon said submarine, and means for coupling the unit nets.

13. A device for destroying submarines comprising a series of units coupled together each unit including a buoyant member, a net pendent therefrom, bombs normally sup-

ported by the buoyant member, means connected with the net and bombs whereby an abnormal downward pull set up by a submarine enmeshed in the net releases the bombs to drop upon said submarine, and means for reefing the nets for use in shoal water.

14. A device for destroying submarines comprising a series of units coupled together each unit including a buoyant member, a net pendent therefrom, bombs normally supported by the buoyant member, means connected with the net and bombs whereby an abnormal downward pull set up by a submarine enmeshed in the net releases the bombs to drop upon said submarine, and brails for reefing the nets for use in shoal water.

15. A device for destroying submarines comprising a series of units coupled together each unit including a buoyant member, a net pendent therefrom, bombs normally supported by the buoyant member, means connected with the net and bombs whereby an abnormal downward pull set up by a submarine enmeshed in the net releases the bombs to drop upon said submarine, and brails for reefing the nets for use in shoal water said brails also being adapted to connect adjacent unit nets.

16. A device for destroying submarines comprising a series of units coupled together each unit including a buoyant member, a net pendent therefrom and having flexible wire laterals provided with an eye in each end and also having more flexible verticals secured to the laterals at regular intervals, bombs normally supported by the buoyant member, means connected with the net and bombs whereby an abnormal downward pull set up by a submarine enmeshed in the net releases the bombs to drop upon said submarine, and brails bent to the lowermost lateral eyes and rove up through the other adjacent lateral eyes to the buoyant members.

In testimony whereof, I have signed my name to this specification.

SYDNEY I. PRESCOTT.
